CIGAR LIGHTER

Filed Oct. 17, 1927

Inventor
Charles Spitzer

By *Philip A. Fenell*
Attorney

UNITED STATES PATENT OFFICE

CHARLES SPITZER, OF WARRENSBURG, ILLINOIS

CIGAR LIGHTER

Application filed October 17, 1927. Serial No. 226,671.

The invention relates to cigar lighters and has for its object to provide a device of this character comprising a supported contact plate, against which the wick end of a fuel receptacle normally engages and to hingedly mount said fuel receptacle at its outer lower end, and to provide a spring cooperating with the outer side of said receptacle and forming means for normally forcing the receptacle 5 towards the supported contact plate, said hinging to one side of the receptacle forming means whereby upon breaking of the spring said receptacle will move by gravity to engaging relation with the contact plate, thereby 10 allowing the continued use of the device.

A further object is to provide the lower end of the receptacle with a contact arm extending through an aperture in the casing and positioned whereby upon rocking of the receptacle outwardly, said contact member will engage a leaf spring supported contact member for closing a circuit and causing a wick to be ignited in the upper end of the receptacle through a jump spark.

25 A further object is to form the supported contact plates relatively wide whereby a large sparking surface is provided and at the same time a surface which will cover the entire end of the bevelled wick carrying tube, thereby insuring the smothering of the flame when the receptacle moves to inoperative position and a closure for the tube for preventing evaporation of the gasoline within the receptacle.

35 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

40 In the drawing:

45 Figure 1 is a side elevation of the cigar lighter, part of the casing being broken away to show the ignition coil therein.

50 Figure 2 is an enlarged vertical transverse sectional view through the upper end of the lighting device.

Figure 3 is a top plan view of the lighting device.

Referring to the drawing the numeral 1 designates the body of the casing, which body is provided with a top 2, preferably formed 55 from insulating material, for instance wood. Extending upwardly from the upper side of the top 2 is a tubular member 3, on the upper end of which is secured by means of a screw 4, a contact plate 5, which contact plate inclines 60 upwardly and forwardly at an angle corresponding to the angle of the upper end of the wick tube 6, which wick tube is carried by the cap 7 of the fuel receptacle 8. The contact plate 5 is wider than the wick tube 6, therefore 65 forms a closure for the upper end of the tube when the receptacle is in inoperative position as shown in Figures 1 and 2, consequently gasoline or other fuel within the receptacle 8 will not easily or quickly evaporate, therefore the amount of fuel necessary to maintain the device in operation is reduced to a minimum. By having the plate 5 relatively wide so that it will cover the upper 70 end of the wick 9, consequently when the receptacle moves to inoperative position will smother the entire flame on the upper end of the wick.

75 Secured to the upper side of the top 2 by means of a screw 10 is a hinged leaf 11, to 80 which is hingedly connected at 12 the receptacle 8 and mounted on the upper side of the hinge 11 and held by the screw 10 is a leaf spring 13, which leaf spring engages the 85 outer side of the receptacle 8 and forms means for forcing the same inwardly to the position shown in Figure 2 after a lighting operation. It will be noted that the hinging point 12 of the receptacle 8 is to the outer side thereof, consequently, if for any reason the spring 13 90 should break, the receptacle would move to inoperative position upon release of the handle member 14 by gravity, as it is hinged to one side, therefor in case of spring breakage the device would continue in operation, 95 and as the spring is a simple leaf spring within easy reach, it is obvious the spring can be easily replaced and by an unskilled person if desired, however at no time will it be necessary for the lighter to be removed 100

from the counter upon breaking of the spring. Extending downwardly from the under side of the receptacle 8 and through an opening 15 in the top 2 is a conductor arm 16, which conductor arm, upon outward tilting of the receptacle 8 engages a contact member 17 supported by a leaf spring 18, thereby closing a circuit over the wires 19, 20, and 21, through the spark or ignition coil 22 and battery 23, the wire 21 being connected to the screw 4 and the wire 20 to the screw 10, therefore it will be seen that a circuit will be completed through the receptacle 8, wick tube 6, over a gap between the wick tube and the plate 5, and thence over the wire 21. By providing the ignition coil 20, it is obvious that a relatively long jump spark is provided between the wick spout and the plate 5, thereby insuring a positive lighting of the wick. 20 When the handle member 14 is released, spring 13 forces said receptacle to closed position and during the hinging of the receptacle the conductor arm 16 will move out of engagement with the conductor member 17. 25 From the above it will be seen that a cigar lighter is provided which is simple in its construction, positive in its operation, and one which may be cheaply manufactured and sold, and one wherein the minimum amount 30 of parts are used, thereby insuring a positive operation at all times.

The invention having been set forth what is claimed as new and useful is:

A cigar lighter comprising a base, a stationary arm extending upwardly from said base, an inclined contact plate carried by said arm, a hinged leaf secured to the base, said leaf being hingedly connected to the lower outer side of a fuel receptacle, a leaf spring 35 carried by the hinged leaf and engaging the outer side of said receptacle above the hinging point, a leaf spring carried contact beneath the base, a contact arm carried by the lower end of the fuel receptacle and extending 40 through an aperture in the base and positioned whereby upon outward tilting of the fuel receptacle it will engage the leaf spring carried contact beneath the base, said arm having its lower end curved, thereby 45 forming a cam engaging surface for the contact. 50

In testimony whereof I hereunto affix my signature.

CHARLES SPITZER.
